DESIGN FOR A COMBINATION CLOTHES STAND

Max H. Erlanger, White Plains, N. Y.

Application May 27, 1937, Serial No. 69,575

Term of patent 7 years

To all whom it may concern:

Be it known that I, Max H. Erlanger, a citizen of Germany, and a resident of White Plains, in the county of Westchester and State of New York, have invented a new, original, and ornamental Design for a Combination Clothes Stand, of which the following is a specification, reference being had to the accompanying drawing, forming part thereof.

In the drawing:

I claim:

The ornamental design for a combination clothes stand, as shown.

MAX H. ERLANGER.
